DESIGN FOR A SLIP

Joseph T. Malouf, San Francisco, Calif.

Application March 14, 1941, Serial No. 99,591

Term of patent 7 years

To all whom it may concern:

Be it known that I, Joseph T. Malouf, a citizen of the United States of America, residing in San Francisco, county of San Francisco and State of California, have invented a new, original, and ornamental Design for a Slip, of which the following is a specification, reference being had to the accompanying drawing, forming part thereof, wherein

I claim:

The ornamental design for a slip, substantially as shown.

JOSEPH T. MALOUF.
